SIDNEY E. MORSE AND G. LIVINGSTON MORSE, OF HARRISON, NEW JERSEY.

Letters Patent No. 66,613, dated July 9, 1867.

IMPROVEMENT IN SUBMARINE TELEGRAPH CABLES.

The Schedule referred to in these Letters Patent and making part of the same.

TO ALL WHOM IT MAY CONCERN:

Be it known that we, SIDNEY E. MORSE and G. LIVINGSTON MORSE, of Harrison, in the county of Hudson, State of New Jersey, have invented a new and useful Improvement in Laying and Raising Submarine Telegraphic Cables; and we do hereby declare that the following is a full, clear, and exact description thereof, which will enable those skilled in the art to make and use the same, reference being had to the accompanying drawings, forming part of this specification, in which—

Figure 1, Sheet 1, represents a portion of a submarine cable, laid with angles or curves at intervals, according to our invention, the bottom of the ocean, on which it is laid, being shown, and also a portion of the surface of the water immediately above.

Figure 2, Sheet 2, is an elevation of an apparatus which both indicates the position of the cable and enables us to raise it to the surface at pleasure.

Figure 3 is a peripheral view of one of the buoys, which are connected or incorporated at suitable intervals with the guiding-wire that extends from the surface or signal spar-buoy down to the cable.

Figure 4 is a longitudinal section thereof.

Figure 5 is a detached view, in red outline, of a sparkling vane, which may be put on the top of the signal or sign-post spar-buoy.

Figure 6, Sheet 3, is a detached view of one of the clasps which surround the cable at certain points, and of the hook connected with such clasp.

Figure 7 shows the clasp open.

Figure 8 is a transverse section of the clasp, its hook being also seen in side view.

Figure 9 is a top view of the hook and clasp.

Figure 10 is an under side view of the hook and clasp.

Figure 11, Sheet 4, represents the lifting-buoys S S, a detachable sinking apparatus for sinking it being shown in red.

Figure 12 shows the lifting-buoys S S in the act of descending the guiding-wire.

Figure 6 also shows the lifting-rope Z, after the ring P has engaged the barbs L L.

Figure 6^x shows the ring P attached to the lifting-rope.

The ship in fig. 1, from the difficulty of drawing it otherwise, is represented with its side, instead of its stern, towards the observer.

Similar letters of reference denote like parts.

Submarine telegraphic cables have hitherto been laid as nearly as possible in straight lines on the bottom of the sea, without provision for raising them unbroken to the surface at points between their termini. Consequently, whenever it was desired to make repairs in a submarine cable, or to inspect it for any purpose, it could be done only by breaking the cable, and then lifting its parts, or by raising one of the ends and under-running the cable until the place which required examination had been reached, it not being practicable to raise a cable which has been laid in one continuous straight line at intermediate points, by grappling and lifting it from the bottom of deep water, because the cable is incapable of the requisite elongation, and therefore, unless its strength can endure the strain produced by dragging its ends towards each other, it must part.

Our invention renders it possible to raise a submarine cable unbroken at any assigned points on the line, and it consists in a novel method of laying the cable, and also in the device of an apparatus for raising it at pleasure.

The first part of this invention involves the employment of a vessel which we will call the pilot-vessel, because its usual position will be in advance of the ship that carries and lays the telegraphic cable, and which we will call the cable-ship. The pilot-vessel must have on board a sufficient number of buoys, and a sufficient length of buoy-anchoring rope, both of our peculiar construction. In laying the cable, at any point where it may be intended afterwards to raise it, the pilot-vessel must stop and lie with its bow pointing at right angles to the line of the general course of the cable, until the cable-ship comes up, and, laying the telegraphic cable across the stern of the pilot-vessel, shall pass on, still paying out the cable, and until time enough shall have been allowed for the cable again to touch the bottom, and the catenary curves on each side between the stern of the pilot-vessel and the bottom of the sea shall have been fully formed. A few inches of

the cable, at or near the angle where the two curves meet on the pilot-vessel, may then be placed in a tubular clasp of metal or other suitable materials, and this clasp, within an iron hook, the shank of which is a barbed iron rod, the barbs pointing downwards and outwards, the rod tapering towards the top and attached there to wires, or a wire or other rope, long enough to reach from the bottom of the sea to the surface, and attached at the surface end to a long tapering floating spar or buoy. This portion of the cable, with the tubular clasp and iron hook attached, may then be cast into the sea, and allowed to draw after it, as it sinks, the wires or wire rope, from a drum or coil, over a pulley in the stern of the pilot-vessel, while the vessel itself is simultaneously moving at right angles to the general course of the cable, and until the clasp, and the part of the cable which it encloses, rest upon the bottom of the sea. The spar-buoy may then be lowered and the work of laying the cable at the first buoy station will be completed.

The barbs in the shank of the iron hook must be made to point downwards and outwards for the purpose of permitting a ring at the end of a strong lifting-rope to run freely over them in its descent, and when the lifting-rope is drawn up, causing it to catch under them and thus enable the operators to raise the cable, as hereinafter explained.

The wires extending from the bottom of the sea to the surface can be twisted, in nearly the whole of their course, into a wire rope, but at suitable intervals may be made to embrace hollow glass spheres, or other buoyant bodies, inserted thus in the rope for the purpose of diminishing its weight in the water.

The spar-buoy may be, if deemed advisable, several hundred feet long, and in the widest part, which should be near its lower extremity where it will lie in still water, may be five or six (5 or 6) inches thick, but at its upper end, which will pass through and rise above the waves, need not be larger than an ordinary fishing-pole. To increase its buoyancy, it may be made hollow, and, on its upper end, which will rise high above the surface of the sea, it may bear a vane or sign with figures to designate the latitude and longitude of its position. The spar-buoy is to have sufficient buoyant power to support the weight of the wires or wire rope, and the latter is to have sufficient strength to hold the spar-buoy securely against the force of waves and currents.

The extent and rapidity of the lateral movement of the pilot-vessel from which the wire rope runs out in laying the curved part of the telegraphic cable must be such as to secure that they will descend without kinking or twisting on themselves, and the wire rope may be strong enough to aid in giving direction to this part of the cable as it descends, but it is not meant to be strong enough to sustain its weight. If necessary to sustain the weight of this part of the cable while laying it, a strong rope of a length equal to the depth of the sea, with a hook attached, may be used for the purpose. The hook of this rope should be passed under one of the barbs L L, fig. 6. After the cable is laid with this rope, the hook will drop and disengage itself from the barb, and the rope may be then drawn on board the vessel, leaving on the bottom of the sea the cable, with its clasp and barbed hook, all connected with the surface by the guiding-wire and the spar-buoy.

When the work of laying the cable at the first buoy station is completed the pilot-vessel may proceed to assume its position in advance of the cable-ship, and proceed to the second station, where the process of receiving the telegraph cable across its stern and laying the second curved part will be repeated, and so on at every buoy station on the line. To raise the cable when thus laid, take a strong rope of sufficient length to reach the bottom of the sea, attach a strong ring eight or ten (8 or 10) inches in diameter at one end, and passing it over the spar-buoy let it run down the wire rope until it passes the barbs or points of the hook at the bottom. On pulling the rope upwards the ring will then be caught by the barbs, and the part of the cable to which the clasp is attached can be raised to the surface without disturbing the straight parts of the line. In raising the curved part of the cable by these means, the pilot-vessel should be moved meanwhile in a direction opposite to that pursued in laying it. This device will enable us to raise the cable for repair, or for examination, or for sending messages to either of the shore ends without breaking it. The cable, when thus laid, can also be raised by attaching the ring P to a buoy or buoys, S S, composed of large glass spheres, encased in a wooden or other suitable case or cases, loaded with a weight sufficient to sink them, which weight will draw down the buoy or buoys until the ring has passed below the barbs L, when the weight can be automatically detached by means of its contact, or the contact of some of its attachments, with the bottom of the ocean, or by any other convenient method, leaving the buoy or buoys free to raise the cable to the surface. A detachable weight or weights, like those shown in red in figs. 11 and 12, can be used for this purpose. The letter A, fig. 1, designates a telegraphic cable which has been laid according to our invention. In laying the cable we employ a pilot-vessel, which takes its place at any assigned point on the line of the general course of the cable, with its bow pointing at right angles to that line. The cable is passed from the cable-ship over and across the stern of the pilot-vessel, and hangs down from it, forming catenarian curves (like those seen at D D, fig. 1,) on each side between it and the bottom of the sea. After the cable-ship may have passed beyond the pilot-vessel the telegraphic cable is laid in its general course, in a straight line, as before, until the next buoy station is neared, when the pilot-vessel, with its buoys and buoy-anchoring ropes on board, having completed its work of laying the catenarian curves at the first buoy station, and assumed its position in advance of the cable-ship, will a second time come to, and with its bow pointing at right angles to the line of the general course of the telegraphic cable, wait until the cable-ship a second time comes up and lays across her stern the cable, which then again assumes the form of catenarian curves. The process of attaching the tubular clasp and the hook, and laying the catenarian curves will then be repeated, and this whole operation will be resumed at each of the buoy stations through the whole route. The letter E, fig. 6, designates a hinged clasp, whose halves, when shut, form a tube that encloses the cable. In this example the clasp is kept closed after the cable has been placed in it, by means of a key or pin, F, that goes through perforated arms, G, which extend radially from the edges of the two halves of the clasp, the arms, which are adjacent to each other when the leaves are shut, being made to pass each other, so that the pin or key F will go through them, and so lock the clasp. The interior of the clasp may,

if desired, be lined with a cushion of cloth, leather, or any suitable material, to protect the cable from injury by abrasion. The clasp E is connected with wire rope H (whose upper end terminates in a spar-buoy I) by a hook, J, which underlies the bottom of the clasp, and is fastened thereto by a pin, K, that is inserted through the middle leaves of the hinge of said clasp after these leaves are themselves projected through the bottom of the hook, as is most clearly shown in figs. 6 and 10, sheet 3. The shank of the hook J is provided with barbs or points, L, projecting downwards and outwards, and the wire rope is connected to the shank of the hook by a conical nut, O, fig. 8, to an eye, in whose pointed end the wire is fastened, while the broad end of the nut is screwed upon the end of said shank. Any other convenient mode of connecting the hook J and wire rope H may be adopted, which will enable the lifting-ring, hereinafter mentioned, to run down from the wire and get below the barbs L. The wire rope H is made as light as possible, so that the spar-buoy, attached to its upper end, need not be very bulky. We have made it, in this example, of several strands, and have incorporated with them, at proper intervals, hollow glass spheres, M, M, fig. 4, sheet 2, hermetically sealed, the glass being only sufficiently thick to resist the pressure of the sea to which they will be exposed, and containing air sufficient to make them as buoyant as possible. The hollow glass spheres are enclosed within a wooden or other casing, N, to protect them from fracture, the casing being pointed at each end to allow the lifting-ring to slide over it with facility. The strands of the wire rope embrace the casing lengthwise, lying in longitudinal grooves, the places of which, as well as the strands, are indicated in figs. 2 and 3. The strands can be kept in place in their grooves by means of bands, which may themselves be sunk in circumferential grooves. The glass spheres and casings are to be as numerous as are necessary to make the weight of the wire rope of a specific gravity as near to that of water as is desired, the advantages of this device being, first, that it enables us greatly to reduce the size of the spar-buoy, and secondly, to use a wire rope of a size and strength barely sufficient to hold the said spar-buoy, and to serve as a guide for the lifting-ring when it is lowered on it to catch upon the barbs. The lifting-ring P, fig. 6X, is a stout metallic ring of a size sufficient to pass over the spar-buoy I and casings N of the wire-rope buoys, and the ends of the barbs L. It is secured to one end of a strong rope, of a length sufficient to reach from the surface to the bottom of the sea.

When the slack or curved part of the cable is to be raised to the surface for repair or for any other purpose, the ring P is passed over the spar-buoy I, and allowed to run down the wire rope H till it gets below the barbs. On pulling it upwards it catches under the barbs, and by applying sufficient power to hoisting the rope attached to it, the slack part of the cable to which the clasp E is connected will be raised to the surface. During the operation of hoisting, the vessel from which the lifting-ring was lowered should be moved towards the line of the straight portion of the cable, so as to relieve the cable from unnecessary strain. The guiding-wire is connected with the lower end of the spar-buoy by passing it through the small end of a long and tapering conical tube or ferrule, Q, the broad end of which passes over and encases the lower end of the buoy. The small end of this conical tube may be lined or cushioned on the inside with leather or other suitable material, (as seen at R, figs. 3 and 4,) which is to project beyond the end, so as to diminish gradually the rigidity and prevent wear and damage to the wires or wire rope from sudden jerks by the action of the waves. The same device may be used at the ends of the casings which enclose the buoys M. (See figs. 3 and 4.) The spar-buoy may have a sparkling vane or other device on it which will readily attract the eye, and such device may have inscribed thereon the degrees of latitude and longitude of its locality. Figure 5 shows such a vane in red. Vessels which sail near the line of the cable may be furnished with rings, P, fig. 6X, and lifting-ropes, and with a Morse or other telegraphic apparatus, so that if occasion arises to send a message to either end of the line the cable may be raised and communication may be had with the offices at the ends of the line by temporarily connecting such telegraph apparatus with the conducting-wire of the cable. The cable may be raised also at any time for the purpose of giving a fresh impulse to the electric current, when from any cause the current from the shore ends is weak, using for that purpose a relay instrument according to the method patented by Professor Morse, and often applied to land telegraphic lines. Fig. 1 represents a vessel that has been engaged in raising the cable at the angle of one of its curves, and it shows also a boat, W, from which a grappling-ring, like P, has been lowered, around a guiding-wire for the purpose of engaging the barbs, and thereby raising the cable. In raising any of the curved portions of the cable the vessel employed in the operation should be moved towards the line of the general course of the cable, as is shown in the case of the boat W, represented in fig. 1. The arrow indicates the direction.

We do not limit ourselves to making the rope H of wire, as it may be made of other material than metal, nor do we confine ourselves to the use of glass buoys of spherical form, as hollow glass vessels of other forms may sometimes be used with advantage.

Claims.

Having thus described our invention, what we claim as new, and desire to secure by Letters Patent, is—

1. Laying a submarine telegraphic cable at assigned places on the line, over a floating body, and then after the catenarian curves on each side are fully formed, depositing the part of the cable included in these curves on the bottom of the sea at right angles, or at nearly right angles, with the main line, so that it may be raised unbroken to the surface from deep water, substantially as described.
2. The formation of a floating buoy, whose lower, larger, and more buoyant part shall always be in deep and comparatively still water, below the violent action of the waves, while the upper part, which is to pass through and rise above the waves, shall present a small surface to their destructive power.
3. The combination of a sliding-ring, a lifting-rope, a guiding-wire or rope, and a hook with a barbed shank, to lift a cable or weight in the water, substantially as described.
4. The combination of a sliding-ring, a buoy or buoys, loaded with a weight that sinks them, a guiding-

wire, a hook with a barbed shank, and an apparatus to detach the weight at the proper time from the buoy or buoys, to raise a cable or other body in the water.

5. We also claim the hook J in combination with the tubular hinged clasp E, substantially as set forth.
6. We also claim the combination of a rope, H, with hollow glass vessels fastened and incorporated therein, so as to diminish the specific gravity of said rope, substantially as described.
7. We also claim protecting the hollow glass vessels by casings of wood or other suitable material, and passing the strands of the rope over the casings in grooves made for the purpose, substantially as described.
8. We also claim connecting a buoy-anchoring rope or a guiding-rope with its encased buoys and its floating buoy by cushioned ferrules, with projecting cushions to diminish the liability to wear at these points from the action of the waves on the floating buoy, substantially as described.

The above specification signed by us the 12th day of December, 1866.

SIDNEY E. MORSE,
G. LIVINGSTON MORSE.
